(57) The ornamental design for a griddle for barbecue, as shown and described.

DESCRIPTION

FIG. 1 shows a top perspective view of the griddle for barbecue.

FIG. 2 shows a bottom perspective view thereof.

FIG. 3 shows top view thereof.

FIG. 4 shows a bottom view thereof.

FIG. 5 shows a front view of the griddle for barbecue, the opposite side being a mirror image thereof; and,

FIG. 6 shows a left side view of the griddle for barbecue, the opposite side being a mirror image thereof.

The broken lines shown in the drawings are for illustrative purposes only and form no part of the claimed design.
